UNITED STATES PATENT OFFICE.

EDWARD A. FIELD, JR., OF OAK PARK, ILLINOIS, ASSIGNOR OF ONE-FOURTH TO
EDWARD A. FIELD, SR., OF CHICAGO, ILLINOIS.

GOVERNOR.

1,354,608.

Specification of Letters Patent.

Patented Oct. 5, 1920.

Application filed April 17, 1919. Serial No. 290,739.

To all whom it may concern:

Be it known that I, EDWARD A. FIELD, Jr., citizen of the United States, residing at Oak Park, county of Cook, State of Illinois, have invented certain new and useful Improvements in Governors, of which the following is a specification.

This invention relates to improvements in governors.

10 My improved governor is especially designed by me as a governor for internal combustion engines, although certain features are desirable for use in other relations.

15 The main object of this invention is to provide an improved governor for internal combustion engines which is sensitive and accurate in its control and at the same time one which is durable and compact in structure.

Further objects, and objects relating to structural details, will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing, forming a part of this specification, in which:

30 Figure I is a plan view of an internal combustion engine embodying the features of my invention.

Fig. II is a detail end elevation of the structure shown in Fig. I.

Fig. III is a detail view of the governor parts with the housing mainly broken away.

Fig. IV is a detail section on a line corresponding to line 4—4 of Fig. III.

Fig. V is a detail vertical section on a line corresponding to line 5—5 of Figs. I, II, III and IV.

Fig. VI is a detail vertical section on a line corresponding to line 6—6 of Figs. I, IV and V.

Fig. VII is a detail section on a line corresponding to line 7—7 of Figs. IV and V.

Fig. VIII is a detail vertical section on a line corresponding to line 8—8 of Figs. I and IX, showing a housing for the valve connecting link and valve connection.

55 Fig. IX is a detail section on a line cor-

responding to line 9—9 of Figs. II, III and VIII.

In the drawing similar reference characters refer to similar parts throughout the several views, and the sectional lines are taken looking in the direction of the little arrows at the ends of the section lines.

Referring to the drawing, 1 represents the body of an internal combustion engine having horizontally disposed opposed cylinders. As the details of the engine form no part of this invention they are not further described herein.

The connection from the carburetor 2 to the manifold 3 is through the pipe 4. This pipe is controlled by the valve 5,—see Fig. JX. This valve is of the butterfly type and has an arm 6 on its stem 7. A housing 8 is provided for this arm.

On the top of the engine body 1 is a housing 9 for the governor mechanism. This comprises a driven shaft 10 having a driven gear 11 thereon meshing with the driving gear 12 on the shaft 13. This shaft 13 is preferably the cam shaft of the engine, but the cams are not illustrated as they form no part of this invention.

The rear end of the shaft 10 is supported in a bearing 14 in the rear wall 15 of the housing 9, while the front end is supported in a bearing 16 carried by a removable plate 17 closing an opening in the front wall 18 of the housing, so that the shaft and the parts mounted thereon may be removed through the opening when this plate is removed.

On the front side of the gear 11 is a bracket 19 having spaced arms 20 thereon between which the arms 21 of the governor weights 22 are pivoted. These arms 21 have extensions 23 which project inwardly to engage the ends of the thrust rods 24 which project through the gear 11 from the thrust sleeve 25 by which they are carried.

The sleeve 25 carries an anti-friction thrust collar 26. Below the shaft 10 is a rock shaft 27 having a pair of upwardly projecting arms 28 thereon which engage the thrust collar 26 on opposite sides of the sleeve. The rock shaft 27 is carried by pivot bearings 29.

At one end of the rock shaft is an upwardly projecting arm 30 connected to the actuating arm 31 at 32 and 33, the lower end of the actuating arm having an offset 110

therein to position the rock shaft and being slotted at 34 to receive the bolt 33, thus permitting the adjustment of the actuating arm on the fixed arm 30.

5 The upper end of the lever or arm 31 is connected by the link 35 to the arm 6 of the valve. The coiled spring 36 is secured to the actuating arm 31 and to an adjusting screw 37 disposed through the front wall 9 of the housing, so that by adjusting the tension of the spring the action of the governor weights is controlled.

10 My improved governor is very sensitive and effectively controls the valves so that 15 a uniform speed of the engine may be maintained.

I have not attempted to illustrate or describe certain modifications or adaptations 20 of my improvements which might be desirable for embodiment in other relations or adaptations to other engines, as I believe the disclosure made will enable those skilled in the art to which my invention relates to 25 embody or adapt the same as may be desired.

Having thus described my invention, what I claim as new and desire to secure by Letters Patent is:

1. In a governor for internal combustion 30 engines, the combination with an inlet valve and a housing therefor, of a governor housing, a shaft provided with a driven gear, a governor weight carrying bracket mounted on one side of said gear, governor weights 35 provided with arms disposed through said gear and pivoted on said bracket, a thrust sleeve mounted on said shaft at the other side of said gear and provided with a thrust collar, thrust rods on said thrust sleeve projecting through said gear to coact with the 40 governor weight arms, a rock shaft having a pair of arms spaced to embrace said thrust sleeve and engage said thrust collar, said rock shaft also having a rocker arm thereon, 45 an actuating arm adjustably secured to said

rocker arm, an adjustable governor spring connected to said actuating arm and to said housing, a link connecting said valve to said actuating arm, and a tubular housing for said link extending from said governor housing to said valve housing. 50

2. In a governor for internal combustion engines, the combination of a shaft provided with a driven gear, a governor weight carrying bracket mounted on one side of said gear, governor weights provided with arms disposed through said gear and pivoted on said bracket, a thrust sleeve mounted on said shaft at the other side of said gear and provided with a thrust collar, thrust rods on said thrust sleeve projecting through said gear to coact with the governor weight arms, a rock shaft having a pair of arms spaced to embrace said thrust sleeve and engage said thrust collar, said rock shaft 65 also having a rocker arm thereon, an actuating arm adjustably secured to said rocker arm, and an adjustable governor spring connected to said actuating arm and to said housing. 70

3. In a governor, the combination of a shaft, governor weights, a member rotatable with said shaft and on which said governor weights are pivotally mounted, a thrust sleeve mounted on said shaft to be actuated 75 by said governor weights and provided with a thrust collar, a rock shaft having a pair of arms spaced to embrace said thrust sleeve and engage said thrust collar, said rock shaft also having a rocker arm, an actuating 80 arm adjustably connected to said rocker arm, and a governor spring connected to said actuating lever. 85

In witness whereof, I have hereunto set my hand and seal in the presence of two witnesses.

EDWARD A. FIELD, JR. [L.S.]
